210,429

AIR CONDITIONING CABINET FRONT OR SIMILAR ARTICLE

Joseph B. Federico, Rochester, N.Y., assignor to Carrier
Corporation, Syracuse, N.Y., a corporation of Delaware

Filed Mar. 1, 1967, Ser. No. 6,024

Term of patent 3½ years

(Cl. D23—141)

FIGURE 1 is a front elevation of an air conditioner cabinet front or similar article embodying my new design;

FIGURE 2 is a cross sectional view taken along line 2—2 of FIGURE 1;

FIGURE 3 is a cross sectional view taken along line 3—3 of FIGURE 1;

FIGURE 4 is a cross sectional view taken along line 4—4 of FIGURE 1; and

FIGURE 5 is a cross sectional view taken along line 5—5 of FIGURE 1.

I claim:

The ornamental design for an air conditioning cabinet front or similar article, substantially as shown.
